UNITED STATES PATENT OFFICE.

TIMOTHY C. MANNING, OF OMAHA, NEBRASKA, ASSIGNOR OF ONE-HALF TO SAMUEL P. MASON, OF OMAHA, NEBRASKA.

GRAIN-DOOR REMOVER.

1,332,404.

Specification of Letters Patent.

Patented Mar. 2, 1920.

Application filed September 13, 1918. Serial No. 253,965.

To all whom it may concern:

Be it known that I, TIMOTHY C. MANNING, a citizen of the United States, residing at Omaha, in the county of Douglas and 5 State of Nebraska, have invented certain new and useful Improvements in Grain-Door Removers, of which the following is a specification.

This invention relates to a grain door 10 mover, and has for its object to provide an implement consisting of few and simple parts which may be economically manufactured and which will be convenient in use for removing the boards, plank or other 15 strip-sections from the posts of the doorway of a grain car readily and in such a manner that splitting or injury of the lumber may be avoided.

It is well known that large quantities of 20 lumber are wasted in shipping grain on railway cars, the plank or board strips employed and which are nailed to the inner sides of the door posts as a substitute for doors, generally being cut, split or otherwise 25 injured in order that the grain may be removed, and since the lumber used must be of good quality, the financial loss, each year, is very great. The invention includes 30 a fulcrum-plate for engaging a door-jamb and a lever so arranged that the boards may be pressed inwardly against the force or outward pressure of the grain, and may be detached from the posts or door-jams without injury.

The invention consists of the novel construction, combination and arrangement of parts as described herein and claimed, and as illustrated in the accompanying drawing, wherein,—

Figure 1 is a transverse section through a part of a grain car showing a side view of the device, the position of parts showing the lever before it has been moved for removal of a board or section. Fig. 2 is a 45 similar view to that shown in Fig. 1, showing the position of the lever after it has been swung downwardly for detaching a board or section. Fig. 3 shows an end view of the fulcrum-plate. Fig. 4 is a side view of the 50 same. Fig. 5 is a plan view of the doorway, the door-jams being in section, the position of parts being the same as shown in Fig. 1. Fig. 6 is a side view of the lever.

The invention is illustrated in connection 55 with a grain car 7, the pair of door-jams for

the doorway 8 being indicated at 9. At 10 are indicated board or plank strips disposed edge to edge upon the inner side of the door-jams, these being secured to the jambs, according to custom, by nails α , as a 60 substitute for a door, before the grain π is deposited in the car; and before unloading the car, a removal of the strips 10 is necessary.

In order that the boards may be removed 65 without material injury I provide a fulcrum-plate 11 having a wing 12 preferably provided at its terminal with transversely projecting teeth 13, the wing 12 being disposed substantially at right angles to the 70 plate so that it may engage that side of a door-jamb above the upper edge of the uppermost board or strip 10, with the plate 11 disposed adjacent to said door-jamb, as best shown in Fig. 5.

The plate 11 is preferably of elongated 75 form so that its lower end may be provided with a contact-finger or spacing-member 14, somewhat remote from the wing 12; and projecting from the same side of the plate, 80 midway between the wing and finger 14, is a second contact-finger or spacing-member 15, being a part of a stationary pivot-pin 16 which projects outwardly from the opposite side of the plate.

At 17 is indicated a hand-lever or operating-bar, mounted between its ends upon the pin 16, said lever preferably being provided at its end with a toothed swivel or rack-bar 18, its pivotal mounting being indicated at 19. Numeral 20 indicates a slot 90 which is formed longitudinally in the lever adjacent to its rack and having recesses opening on the slot at intervals, as indicated at b , c and d .

By use of the device thus described, the strips 10 may be quickly detached from the door-jists. In operation, the device is first disposed as shown in Fig. 1, its upper end engaging the inner side of the door-jamb 100 above the strips 10, the rack engaging the outer side of the uppermost strip, and by moving the lever in a limited circle's arc the strip may be readily moved inwardly of the car without injury, regardless of the 105 pressure of the grain or resistance occasioned by the nails. After the uppermost strip has been detached, the plate 11, which provides the fulcrum for the lever, is moved downwardly on the post to permit the rack- 110

bar to engage the strip next lower or adjacent to the one just removed, and in like manner all of the strips 10 may be detached, a single swinging movement of the 5 lever being sufficient for detaching each strip.

While I have described the exact construction preferred, I do not wish to be understood as limiting myself in this respect, and 10 I may change minor details, and may change form and size of parts and also their proportions as may be found to be of advantage since it is the invention as claimed that determines its scope.

15 The use of the slot 20 is a feature of advantage since the weight of the grain will tend to press a strip 10 outwardly against the door-jambs after the strip has been detached, and on account of the provision of 20 the slot, the lever may be moved longitudinally, independently of the plate 11, for detaching the rack-bar from the strip, after the latter has been detached.

Also, since some of the nails employed 25 may have an extreme length, the recesses b, c and d are of advantage so that the strips or sections 10 may be moved inwardly of the car a distance corresponding to the length of the nails, the lever being disposed 30 with the recess d receiving the pin 16 if the nails are of considerable length, the center of the arc of movement for the rack-bar being the pivot-pin 16.

By use of the fingers or spacing-members 35 14 and 15, any lateral swinging movement of the plate 11 will generally be prevented. They are of advantage on account of the uneven surfaces, pockets or depressions which are generally formed in door-jambs 40 of grain cars, incident to their use; and by use of two members 14 and 15, the plate 11 may be maintained at right angles to the boards or sections 10; also the hand-lever may swing freely without engaging the

housing-strip e which is secured to the door-frame and which often projects inwardly of the doorway. 45

It is obvious that the device would be operative if the toothed member 18 was dispensed with, but it is preferred since the 50 stresses are directed to a greater area, which tends to prevent injury to the strips or board-sections. Also, if the slot 20 was omitted, operation in removing the strips would not be prevented, but by use of the 55 construction substantially as shown, operation is convenient and effective, and these features do not add materially to the cost of manufacture.

What I claim as my invention is,— 60

1. A grain door remover comprising a fulcrum-plate having a toothed wing and a spacing finger projecting outwardly from one of its sides, its opposite side being provided with a pivot-pin, a lever provided near 65 one of its ends with a slot for receiving the pivot-pin and having a toothed member pivotally mounted thereon at its end, adjacent to said slot.

2. A grain door remover comprising a 70 fulcrum-plate having a wing projecting outwardly from one of its sides, its opposite side being provided with a pivot-pin, a lever having a slot formed longitudinally therein and having recesses opening on the slot, said 75 lever being adapted to be mounted with its slot and one of said recesses receiving said pivot-pin, a toothed member pivotally mounted upon the lever adjacent to said slot, the terminal part of said wing being 80 provided with projections.

In testimony whereof I have affixed my signature in presence of two witnesses.

TIMOTHY C. MANNING.
